Igor B. Bensen, Raleigh, N.C., assignor to Bensen Aircraft Corporation, Raleigh, N.C., a corporation of North Carolina

Application July 6, 1956, Serial No. 42,155

Term of patent 14 years

(Cl. D71—1)

Figure 1 is a side elevational view of a glider embodying my new design, the opposite side thereof being substantially the same as the side shown; and

Figure 2 is a front perspective view of the glider.

The dominant features of the design reside in the portions shown in the full lines.

What is claimed is:

The ornamental design for a glider, as shown and described.
